UNITED STATES PATENT OFFICE.

MARSHALL B. LLOYD, OF MENOMINEE, MICHIGAN, ASSIGNOR, BY MESNE ASSIGNMENTS, TO HEYWOOD-WAKEFIELD COMPANY, OF BOSTON, MASSACHUSETTS, A CORPORATION OF MASSACHUSETTS.

REED-WEAVING MACHINE.

Application filed May 28, 1917. Serial No. 171,431.

To all whom it may concern:

Be it known that I, MARSHALL B. LLOYD, a citizen of the United States, and a resident of Menominee, county of Menominee, 5 and State of Michigan, have invented a certain new, useful, and Improved Reed-Weaving Machine, of which the following is a specification.

My invention relates generally to improvements in machines for weaving fabric of which reed is characteristic, and which is composed of a plurality of spaced members called stakes, upon which long strands called fillers are woven, over some of the 15 stakes and under others.

The object of applicant's invention is to produce a machine wherewith reed fabric can be produced mechanically. Another object of applicant's invention is to produce 20 a reed weaving machine which shall be simple in construction; which shall require but little space; which shall produce in a given time, many times the amount of fabric now producible by hand; which shall 25 produce a fabric of greater uniformity and increased strength; which shall be operable by unskilled workers; which shall produce a given fabric with less material; which may be quickly made ready for the weaving 30 operation and in which the woven fabric can be quickly and easily removed from the machine.

Other objects of my invention are to provide a weaving machine which can be constructed at a low expense and which can be maintained in working order with a minimum of attention and cost.

My invention consists generally in the form, construction, arrangement, and co-operation of the parts whereby the above named objects, together with others which will appear hereinafter, are attainable and my invention will be more readily understood by reference to the accompanying drawings which illustrate that form of my invention which I consider at the present time, the preferable form. In the said drawings,

Fig. 1, is a general view of the machine partly in elevation and partly in section showing a portion of the fabric completed.

Fig. 2, is a transverse vertical section substantially on the line 2—2 of Fig. 1,

only part of many similar parts being shown for the sake of clearness of illustration.

Fig. 3, is an enlarged fragmentary plan view substantially on the lines 3—3 of Figs. 1 and 2.

Fig. 4, is a detail view in elevation of the portion of the machine where the filler 60 strand is inserted.

Fig. 5, is a fragmentary plan view of that portion of the machine illustrated in Fig. 4.

Fig. 6, is a detail view, in elevation, substantially on the lines 6—6 of Figs. 4 and 5.

Fig. 7, is a perspective view illustrating one of the filler strand packing arms and associated mechanism.

Fig. 8, is a plan view of the packer arm 70 and associated guiding means.

Fig. 9, is a side elevation of the filler strand tensioning and payout mechanism.

Fig. 10, is an elevation of the tensioning and payout mechanism.

Fig. 11, is a plan view of means for holding the stakes in proper spaced relation; and

Fig. 12, is a side elevation of the stake holding means.

Fig. 13, is a detail sectional view illustrating means for repositioning the spring stake holding means.

That embodiment of my invention shown in the drawings is characterized by or comprises generally the following parts;

Frame,

Stake holding and positioning means,

Stake manipulating and controlling means,

Filler strand inserting means,

Filler strand packing mechanism,

Reed tensioning and pay out mechanism,

Driving mechanism.

As a matter of convenience, and in order 95 to facilitate and simplify the description and understanding of the machine, I shall describe the parts generally in the order above outlined.

The frame.—The frame is characterized 100 by a base portion 1; filler strand packing mechanism guide portion 2; and fabric limiting portion 3. The base portion 1, comprises a bottom portion 4, upstanding portion 5, and horizontal portion 6. The portion 2, comprises spaced parallel plates 7

and 8 which are connected and rigidly spaced by a plurality of rods 9. Concentrically spaced around the lower plate 7, is a ring 10, which is supported from the upper plate 8 by means of a plurality of rods 11. The rods 9 and 11 are positioned on radial lines (best shown in Fig. 3) and are secured to the plates in a suitable manner, such for example as by nuts 12 and 13, which permit of convenient assembling and demounting of the parts as will be more fully described with reference to the filler strand packing mechanism. The rods 9 and 11 and their fellows form guides for the sliding portions of the filler strand packing means. In Fig. 2, only two diametrically opposite sets of rods 9 and 11 are shown, the other similar rods, which would be seen in this view, being omitted for the sake of clearness and simplicity. The fabric limiting portion of the frame is composed of a ring 15, mounted upon the plate 8, as by means of dowel pins 16 which properly position it and which permit its ready removal and replacement. Secured in the ring 15 and upstanding therefrom are a plurality of members 17, as best shown in Figs. 2, 3, 6, 7, and 8. In Fig. 2, only two oppositely disposed members 17, are shown, the others being omitted for the sake of clearness. I might here state that one member 17, is provided for every stake in the reed fabric, the purpose and function of which will appear shortly. These members 17, are given that shape which is desired in the finished fabric and as will be seen, serve to limit the inward forming tendency of the fabric. The upper portions of the member 17, are secured in a plate 18, which construction rigidly holds various members in proper spaced relation.

Stake holding and positioning means.—The stake holding and positioning means in this instance, is characterized by a circular band or belt 20, having a plurality of spaced holes 21, of a size to accommodate the stakes 22, snugly therein, that is to say, the holes 21, permit the placement of the stake ends therein and hold them frictionally to a sufficient extent to prevent undesired withdrawal or displacement. The band 20, in this instance is severed as at 23, and one portion has an extending eye 24, and the other portion spaced projecting eye portions 25, which straddle the member 24, thus aligning the eye portions and permitting the placement of a pin 26, to hold the band in closed position. The band may thus be readily opened by withdrawing the pin 26, and if desired the stakes may be placed in the belt or band when it is straight and the band closed when the stakes are in position. The stakes may be somewhat more readily placed in the holes when the belt is opened and the curving of the belt serves slightly to pinch the respective stakes. The band with the stakes in position may thus be placed around the members 17, of the fabric limiting portion, placing the same on from above as will be readily understood from the detailed description of the upper portion 70 of the machine or if desired, the band may be wrapped around the member 17, and then fastened to make an endless band or ring. The band 20, abuts the ring 15, containing the member 17, and the stakes upstand therefrom following closely the general course of the members 17. I might here state that I found great difficulty in properly positioning and aligning the stakes so that during the weaving operation they would maintain 80 desired regular spaced relation and would not become bent, kinked, or otherwise injured or displaced by the weaving and packing mechanism. I finally solved this difficult problem in a simple and inexpensive manner. To this end, I form the members 17, of two pieces of relatively thin strap metal 30 and 31 which are suitably secured together against relative movement by any suitable means, such for example, as riveting 85 90 95 100 105 110 115 120 125 130 135 140 145 150 155 160 165 170 175 180 185 190 195 198 200 205 210 215 220 225 230 235 240 245 250 255 260 265 270 275 280 285 290 295 300 305 310 315 portion of a helical spring 43, is accommodated. The spring 43, is of such a size with relation to the plate 40 as to tend to compress itself on the plate and into the 5 groove 42, and is formed with two complete convolutions for every stake of the fabric. The spring is so positioned with respect to the stakes that the stake can be moved into the contiguous V-spaces formed by oppositely disposed portions of the spring as is best shown in Figs. 3, 4, and 5. The stakes may move into this space a certain distance but cannot get out of the spring entirely and the spring serves to carry the stakes in 10 proper spaced relation during the interval in which the stakes are separated from the plate 40 for the insertion of the filler strands. The spring 43, is maintained against undesired shifting or circumferential creeping around the plate 40 by means 15 of studs or pins 45 spaced substantially equidistant between the stakes. A portion 45' of every pin is beveled so that in the event of the spring striking the pin as it returns 20 to position in the groove of the plate 40 after passing around the filler strand inserting means, it will be shifted back into position. The action of the pin in shifting the spring will be readily understood by reference 25 to the detailed fragmentary sectional view Fig. 13, wherein the proper position of the coiled spring is indicated by means of dotted lines and the position in which it sometimes strikes the pin indicated by 30 means of full lines and as a cross section of the spring. The plate 40 is provided with vertical grooves 47, for the accommodation of the stakes, these grooves permitting stakes to lie slightly below or flush with the outermost portion 48, of the plate 40. Thus 35 the upper or free ends of the stakes are held in proper spaced relation and prevented from getting out of their proper grooves. In the instant case, it is desired to provide 40 a fabric in which the filler strand passes over one stake and under the next adjacent stake and to this end I provide means which moves out the upper portion of every other stake together with means for holding such projected stakes out for a period sufficient 45 conveniently to insert the filler strand at which time the stakes are permitted to return to their normal positions in the grooves of the plate 40 and in fact, are actually and positively 50 returned to such positions. The means here shown for manipulating the stakes comprises a wheel 50 having a plurality of projecting somewhat teeth-like portions 51. The wheel 50 is rotatably mounted by means of stud 52, upon a member 53, which is stationary relative to the plate 40. The plate 40 carries spaced studs or pins 54, equal in number to the stakes of the fabric, and in this instance, radially aligned there- 55 with and the wheel 50 carries a gear mem- 60 ber 55, upon its underside with which pins 54, engage. Thus as the plate 40 is driven in the direction of the arrows, by means to be described, the wheel 50 is moved in the direction, indicated by the arrow and the teeth 51 thereof successively engage alternate stakes moving the upper portions of them away from the plate 40. The wheel 50, is arranged adjacent a somewhat V-shaped stake spreader 56, the teeth 51, of the wheel 50 moving the stake, end portions out a distance beyond the outer side of the point 57, of the spreader. Once the stake reaches this position it is caused to move still further away from the plate by engagement with the outwardly extending spreader 56. At this point I arrange a relatively narrow and somewhat blade-like member 60 through the center of which is a tube 61, through which the filler strand 62, passes emanating from the lower end thereof around a very small curve projection 63, as is best shown in Fig. 4. This blade-like member 60 it will be seen is arranged very close to the outer portion of the plate 40 and has a curved outer face 64, over which the stake retaining coil 43, passes, the coil returning to its normal position engaging the groove 42, and the pins 45, so soon as the blade 64, is passed. In this way it will be understood that the filler strand 61, is laid in place to pass over one stake and under the next adjacent stake after which the filler strand is properly packed upon the preformed fabric by means to be shortly described in detail but before describing that mechanism I will point out some further details relative to the filler strand inserting means. I prefer to provide in addition to the stake spreader 56, another lower stake spreader 56' which is 65 constructed similar to the spreader 56, except that its point is somewhat closer to the plate 60 and does not project as far from the plate 60 as does the upper spreader, the object being to support the stake at spaced 70 points to prevent undesired bending or likelihood of becoming entangled with the filler strand inserting means. The arrangement and position of these spreaders, is well shown in Figs. 4 and 6. There is a tendency 75 for the stakes, I find, at times to spring out of their grooves and I have so far found it desirable to prevent any likelihood of such action to provide a coil compression spring 70, which encircles the stakes just 80 below the helical stake guiding spring 43. The upper end of the blade 60 is shaped into tubular form and the blade is held stationary relative to the plate 40, and the stakes by means of a bracket 71, which is 85 mounted upon the member 53, heretofore described. I find that it is necessary to have a fairly accurate adjustment of the blade with respect to the stakes and I, therefore, provide means for adjusting it radially, ver- 90

tically and rotatably. This is accomplished by providing a slot and bolt connection 72, between the bracket 71 and its support 53, and by splitting the end of the bracket 71 and there providing a bolt 73, which can be tightened or loosened to permit raising or lowering of the plate and also to permit rotation of the plate if desired. It will also be understood that the bracket 71 can be swung if necessary from the bolt 72, as a pivot. In this manner, ample and accurate adjustment is provided to the end that the exact distance between the wheel 50 and the stake spreader 56, may be provided which gives the best working action, although this may be varied to some extent without destroying the co-operative relation of the parts. The position shown in the drawings will be found to be substantially correct. I might here add that in order to weave the fabric rapidly and yet to keep the speed of the parts within reasonable limits, I find it desirable, though not necessary, to insert a plurality of filler strands at spaced intervals. In the instant case, I have shown the filler strand inserted at diametrically opposite points and with this construction, a given fabric can be completed in half the time that would be required were a single strand employed or the fabric may be produced in the same time with the machine operating at half the speed. When a single filler strand means is employed it is necessary that an odd number of stakes be employed so that at each revolution the filler strand may pass over the stake which it passed under upon the previous revolution. In the instant case where two filler strands are inserted, an even number of stakes is employed to the same end. While as before stated, it is desirable to weave at a number of points, I have found that this multiple weaving introduces new problems which must be solved before a satisfactory fabric can be produced. These problems relate largely to the proper tensioning of the filler strand and to securing, or rather, placing during each interval of time the same amount of filler strands at one point as is placed at the other feed point. The mechanism which I finally devised to this end will be described later under the head of "Reed tensioning and pay out mechanism." While I am discussing the filler strand inserting means and the contiguous mechanism, I should add that I have so far found it desirable to provide a spring member 80 attached to the stake spreader and which passes upon the inner side of the filler strand inserting plate, the spring being inwardly resilient and causing the ends of the stake which remain in the grooves to be held inward to an extent sufficient to avoid any interference thereof with the inner face of the plate and then to prevent

undue movement of the stakes under the action of the spring 80 (see Fig. 5) I provide an outwardly resilient spring member 81 which in this instance, is mounted upon the bracket 53. Thus a track or causeway 82, is provided between the spring 80 and 81 through which the alternate passive stakes pass. The machine shown is formed to produce a fabric of circular cross section, of diameters differing from top to bottom and with a contour curved with respect to its axis. I might add that such a fabric can be used very extensively for the manufacture of many articles and when a fabric with a curved contour is produced by hand in the hitherto universally customary manner it is a slow, laborious task and even then requires workmen who are highly skilled in the art. I have so far found it most convenient to manipulate the stake ends for the purpose of inserting filler strands when the stakes extend somewhat parallel to the axis of the machine, and I have, therefore, made the machine parts at the upper portion straight for a distance 90 above the line to which the fabric is to be woven. I have also found that there is a tendency for the stakes when approaching and passing the weave point to spring away from their guides 30, of the members 17. It is, of course, particularly desirable that the stakes shall be maintained in their proper spaced relation at this point and for the purpose of returning the stakes to their proper positions at this point, should they become misplaced forward of their proper guide 17, I provide a wheel 90 mounted upon a flat spring 91 which in turn is fastened in a block 92, pivotally mounted in a bracket 93, which is fastened upon the upper portion of the blade 60, through which the filler strand passes. The bracket 93, is split and has a bolt for clamping it upon the plate whereby it can be moved for the purpose of placing the wheel 90 in the exact position necessary to give the best results. I find this position to be substantially as shown in the drawings, that is to say, a little forward of the point where the filler strand is placed between the stakes so that as each stake approaches this point, it is pressed down into its groove by engagement with the wheel and as will be described shortly, the stake is prevented from being carried too much rearwardly by means of the packing finger which at this time, is adjacent the wheel and oppositely disposed therefrom.

Filler strand packing mechanism.—It is very important that the filler strand be properly and uniformly packed if the resulting fabric is to be of a character suitable for use upon high class articles. It will be understood that in this instance where the filler strand is fed between the

stakes at the upper portions thereof, it is necessary to pack the filler strand from a point adjacent its entrance between the stakes to a point contiguous the pre-formed fabric. Obviously as the fabric is formed the extent of the packing varies. It is also necessary that the packing means be so constructed as not to interfere with the insertion of the filler strand. I have also found 5 that extreme care must be used to prevent the packing means from catching upon the stakes throwing them out of alignment, crushing them and ultimately preventing the proper operation of the machine. After 10 much experimentation I have produced the mechanism which I shall now describe and which, while extremely simple, serves admirably to pack the filler strand. Furthermore, not only does this mechanism not dis- 15 align, injure, or crush the stakes, but it actually and positively realigns the stakes between each filler strand feeding period, should they for any reason become disaligned. The character of reed is such that 20 it is likely because of inherent tendencies to assume irregular lines and furthermore, under the action of weaving, the filler strand thereon to be dragged from its proper spaced position. The filler strand pack- 25 ing mechanism here shown is characterized by a weight 90^a which is mounted for vertical sliding movement between adjacent pairs of rods 9 and 11 as by means of stud shafts 91^a and 92^a, passing therethrough. 30 The stud shaft 92^a is provided with rollers 93^a and 94^a, to reduce the friction incident to its sliding motion. In the lower end of the weight, I mount a roller 95, which in turn rests upon a cam 96. 35 The cam 96, as is best shown in Fig. 1, rises from the point 97, to a ridge 98, which is of a width sufficient to support a number of weights 90^a thereon. It will be understood that the cam rises and falls upon 40 each side of the machine (only one-half of the cam being viewed) the purpose being to elevate the weight and to permit its proper descent during each half revolution of the machine, or in other words, to elevate the weight and to permit its descent, once for 45 every filler strand, that is inserted. A stud shaft 91^b, passing through the weight 90^a is inwardly and outwardly extended to form end portions 97^a and 98^a the end portion 50 98^a forming a handle whereby the weight can be manipulated by hand when desired, either to test the packer; to permit release of the fabric; or for such other purposes as may be necessary or desirable. The inner 55 end 97^a, of the stud 91^b, is slotted and the lower end of the upstanding packer arm 99, enters therebetween and is arranged for swinging movement therein by means of the pivot 100. I also prefer to form an elongated slot 101 in the lower end of the packer 60

arm 99 through which the pin 100 passes, the arm 99 being normally pressed upwardly by means of a spring 102 which normally maintains the pivot 100 in the lower portion of the elongated slot 101, the purpose of 70 which will be shortly described. Upon the upper end of the rod 99, I mount a finger 103. The finger 103 has a nose portion 104 which is normally projected through the spaces between the fabric limiting members 75 17, as is well shown in Fig. 3, by full lines, and by dotted lines in Figs. 2 and 6. The normally extended position of the packing finger is also illustrated in Fig. 7. The packing arm is continuously pulled radially 80 outwardly of the machine by means of a tension spring 105, which is attached to and extends between the packer arm and one of the weight studs, in this instance, the stud 91^a, and the outward movement of the 85 finger is limited by means of a collar 106, upon the packing finger 103, which engages the inwardly projecting portion 32, of the member 17, as is probably best shown in Fig. 8. This construction not only limits the 90 outward movement of the finger but also forms a guide directing its to and fro movement in the path in which the fabric is to be formed, which in this instance corresponds to the contour of the member 17. I might 95 here add that this yielding construction of the packer arms permits it readily to follow guides of different forms as may be necessary for the construction of differently shaped fabrics. The cam 96, which raises 100 the weights is stationary with respect to the frame portions 2 and 3, which are given rotation by means described under the heading "Driving mechanism." 105 The cam 96 is held against rotation by means of upstanding rods 120 which are passed through the portion 6, of the frame base and these rods may be vertically adjusted to vary the height of the cam 96 by means of the nuts 121 and 122 engaging the 110 upper and lower surfaces of the base portion 6. Thus as the parts 2 and 3 of the machine are rotated and the cam remains stationary the weights are caused to ride up the inclined portion of the cam thereby elevating the packer arm which follows the guides 115 17, until the rollers 123, upon the upper inner ends thereof engage the frame plate 18, at which time further continued rising of the weight causes the arm to swing inwardly the inward movement continuing until the annular stop 124, is reached at which time the weight 90^a, has also reached the highest portion 98, of the cam which it 120 will be seen is slightly before the point where the filler strand is inserted. The weight rides upon the ridge 98, for a period sufficient to hold the finger in retracted position until it has passed the filler strand at which time the weight is permitted to de- 125 130

scend and so soon as it starts its downward course the packer arm under the influence of the tension spring 105 is immediately drawn radially outward into position between the spaced members 17. It will be understood that the packing finger is now upon the upper side of the filler strand and as it descends hangs upon the filler strand, the weights 90^a being sufficient properly to pack the filler strand into position adjacent the previously laid filler strands of the fabric. Of course, for the first partial revolution the packer arm descends to the dotted position indicated in Fig. 1 or in other words, to the band 20 in which the stakes are mounted but as the filler strands are inserted and the fabric is formed, the weights descend a lesser distance each half revolution. I might here add that accurate adjustment of the packers is unnecessary because the weights simply fall by gravity until the nose 104 of the packing finger engages the pre-formed fabric at which time the weights hang from the fabric until the upward incline of the cam is again reached at which time they are elevated, retracted, held in retracted position for an interval to permit insertion of the filler strand and then re-projected above the filler strand to again descend and cause the proper packing thereon. Again extremely accurate placement of the cam 96, is eliminated by the slotted construction 101 of the lower end of the packing arm 99, which permits taking up of considerable excess motion of the weight 90^a, the compression of the spring 102 being of sufficient strength to cause the packer arm to move in against the tension of the spring 105.

As before stated the stakes may at times become disaligned or spring away from their proper position paralleling the members 17, as for example, the stake may spring into the space between the adjacent members 17, as indicated by the dotted lines in Fig. 7, and unless some means were provided for re-aligning the stakes they would become pinched or wedged between the finger and the member 17, or otherwise becoming entangled thereby stopping the operation of the machine and preventing the formation of a proper fabric. After experimenting with various means to obviate this objection I discovered that by mounting a round projection 131 upon the packer arm 99, which is below the packing finger 103, that as the packer arm is raised and lowered the stake if dis-aligned is replaced to its proper position. This projection 131, in its outermost extent 132, is substantially co-incident with the outer-most portion 30' of the portion 30 of the fabric limiting the elements 17. I find that with this device the machine can be operated at relatively high speed; that the packer arms while thus moving rapidly

back and forth in the grooves will re-align with marvellous dexterity any stakes that have become displaced from their proper alignment with the member 17, and that in the finished fabric the stakes are remarkably straight so much so that the fabric is far superior to the fabric which is producible by the most skilled workers under the hitherto customary hand weaving methods. Thus it will be seen that the stakes are properly aligned and that they are prevented from getting away from the member 17, in the other direction because of the projection 33, against which they normally lie prior to weaving of the filler strand. As before stated in case they should for any reason get out of alignment in that direction they are replaced by the wheel 90, which is prior to the feed, this wheel tending to shove them in the other direction and being prevented from shoving them to an extent too great by means of the projecting nose 104 of the packing finger, which at that time is adjacent to this wheel as will be understood by reference to Figs. 1 and 4.

Reed tensioning and dispensing mechanism.—As before stated it is very important that the tension of the filler strand be maintained constantly to just the right extent, if the fabric is to be uniform in appearance and strength especially is this so where two or more strands are woven simultaneously. I have devised a novel mechanism whereby the filler strand tension can be maintained uniformly throughout the entire extent of the fabric and irrespective of the amount of reed which may be upon the reel. Where a multiple feed is employed such as shown in the instant case not only is it desirable that the tension be uniformly maintained upon each filler strand but it is also desirable that the amount of the material inserted at the two feed points during a given period of rotation be practically the same or there will be a noticeable looseness in one of the filler strands as compared with the adjacent filler strand. The structure which I have designed to this end comprises a wheel having two beveled or angling faces 140 and 141 which are bounded by flanges 142, 143, and 144. The wheel is mounted upon a stud shaft 145, suitably mounted in a bracket 146, and the bracket 146, has a depending portion 147, to which is secured a filler strand guide 148, having separate parts 149 and 150 through which the filler strands pass. As is well shown in Fig. 9, this guide is crimped as indicated at 151 so that when the reed is pulled therethrough it does not pass freely but is retarded to an extent necessary to cause it to be taut between the guide and the tensioning wheels. The filler strands are mounted upon separate spools or reels 160 and 161 which are rotatably

mounted in brackets 162 and 163 carried by a suitable standard 164 (see Fig. 1). From these spools the filler strands pass to their respective hollow guide portions 149 and 150 from whence they pass first around the upper portion of the faces 140 and 141 and thence completely passing around the wheel and finally returning from the lower inclined portion of the face. As the machine 5 operates the reed is drawn from the reels and in passing over the wheels 140 and 141 is put under tension. Each particle of reed must pass substantially twice around the tension wheel which is of constant 10 diameter and hence the tension on the reed is uniform whether there be much or little reed upon the spool or reel. The faces 140 and 141 being of identical size and moving together necessarily pay out accurately 15 measured quantities of filler strands to each feed point. In order to adjust the tension upon the reed, I provide a threaded rod 165 extending from the stud 145 of the tension wheels and upon this threaded rod I 20 mount a thumb nut 166 having a flange 167. Abutting the flange 142, of the tension wheel I place a friction disc 168 preferably composed of fibre and this disc is pressed against the flange of the thumb nut 25 and the friction disc as is well shown in Fig. 10. By this means the tension of the filler strand may be very accurately regulated and the filler strand put under just that degree of tension which gives the best 30 results for the particular filler strand employed. The exact tension necessary will depend somewhat upon the character and size of the filler strand; the size and character of the stakes employed; the size and 35 number of the packing weights as well as other features.

Driving mechanism.—The machine, in this instance, is driven from the drive shaft 110', upon which are mounted loose and 40 fixed pulleys 111 and 112, over which the driving belt 113 operates; through the meshing bevel gears 115 and 116, the vertical shaft 117 carrying the pinion 118 which in turn meshes with the gear 119 bolted to the 45 lower plate 7, of the machine frame. In this manner it will be understood that the frame and parts carried thereby are caused to rotate while the vertical central shaft 110 remains stationary and forms a rigid 50 support for the rotating machine. The shaft in this instance is firmly fixed against rotation by means of pins 120^a which pass through the shaft and the long hub like 55 portion 121^a of the base.

Having thus described in detail the 60 various structural features and their co-operative relation, I shall briefly state the operation of producing a completely woven fabric thereon. To this end let us assume that 65 the band 20 has been removed from the ma-

chine. Stakes of the proper length are then inserted one in each hole 21, provided therefor in the band, the lower ends of the stakes being substantially flush with the lower end of the band. The band containing the 70 proper number of stakes is then placed upon the machine. This may be done either by wrapping the band around the machine and then fastening the abutting ends, or first fastening the belt or band to form a ring 75 as shown in Fig. 11 and then placing same over the top of the machine. To enable placement of the band over the top of the machine and to permit removal of the finished fabric, the plate 40 and all mechanism carried thereby can be bodily lifted from the rest of the machine to facilitate which operation I preferably provide eyes 170 in the upstanding portion 171, of the plate 130 (see Fig. 2). The plate 130 is fixed against 80 rotation by means of set screws 132', which enter a groove 133, in the upper end of the shaft 110. When the part 130 is lifted the plate 40 and mechanism carried thereby is also lifted. In removing the upper portion 85 of the machine the machine screw and loose collar 134 and 135 are first removed. These latter parts enable the plates 40 and 130 to be drawn to position when replaced. In placing the stake band upon the machine, care must be taken to see that the stakes are positioned substantially in front of the portion 30 of the guides 17. The stakes are maintained in the band so that when the band engages the members 17, the stakes will be held a sufficient distance away from the outer surface of the member 17, to permit the insertion of the filler strand therebetween. After the band and stakes are 90 placed in position the head plate 40 and its associated mechanism is lowered into 95 position being accurately guided into proper 100 position by means of dowel pins 41 (see Fig. 2). The free ends of the stakes are then passed under the retaining coil 43, each stake 105 entering its proper groove 47, in the plate 40. The filler strands may be then threaded over and under the stakes from the point of entrance to the belt along the general curved 110 line defined by the various packing fingers or I find that the machine can be started without threading the filler strand over and under these stakes by simply pulling from the reel, a sufficient length of filler strand 115 as when the machine is started the filler strand is automatically laid into position and carried by the packers from the entrance position down to the belt. Continued 120 rotation of the machine upon the vertical stationary shaft 110 quickly lays in sufficient 125 filler strands to form the fabric and when the fabric is formed to proper height the machine is stopped, the incoming filler strands severed, the plate 40 and its associated mechanism raised, the wheels 90 being 130

thrown into the position shown by the dotted lines in Fig. 2, at which time the head can be freely raised. It will now be understood that practically all of the fingers of the packers rest upon the complete fabric and in order to release the fabric it is necessary to move the fingers inwardly. This can be done readily by simply pressing the fingers by hand inwardly and lowering the weight to a position resting upon the cam. When all of the fingers are thus released the fabric can be bodily raised and removed from the machine; the band pulled from the stakes; new stakes inserted; the stakes and band replaced upon the machine; the weaving plate lowered and the machine is again ready for weaving the next fabric. I neglected to state that when releasing the fabric from the machine the auxiliary stake retaining spring 70 is first stretched up over the stake retaining spring 43, and over the top of the stakes so that when the plate 40 is raised there is nothing to catch upon the stakes to cause them to bind and prevent free release of the weaving parts. There are many other ways in which the machine can be made ready for the weaving operation, all of which will readily suggest themselves from this detailed disclosure to those who are skilled in the art. For example, instead of preparing the machine in the manner stated the stake retaining band may be placed upon the machine and then the stakes inserted in the stake holes instead of first placing the stakes in the band when it is independent of the rest of the machine.

While before suggested I wish to add more definitely that fabric of different shapes, within certain limits, can be readily woven upon a machine embodying my invention. This is readily accomplished by lifting the head plate and associated mechanism from the fabric limiting portion 3 and then lifting the fabric limiting portion 3 from the part 2, placing a fabric limiting portion of desired shape on part 2 and replacing the head plate and associated mechanism. The removable dowelled construction enables quick and easy repositioning of the parts. Inasmuch as this complete disclosure will readily suggest to others modified structures whereby the substantial objects and advantages of my invention may be attained I do not wish to be limited to the specific construction herein shown and described except only as may be necessary by limitations in the hereunto appended claims.

I claim:

1. An apparatus for weaving reed fabric and the like embodying therein fabric limiting means (against which the fabric is formed) formed with a plurality of packing finger slots, means for holding the stakes in weaving relation thereto, and means for ef-

fecting the placement of a filler strand upon the outer side of some stakes and the inner side of others, said means including packing fingers operating in said packing finger slots, whereby a fabric can be formed as a separate unit apart from the fabric limiting means. 70

2. An apparatus for weaving reed fabric and the like embodying therein fabric limiting means (against which the fabric is formed) formed with a plurality of packing finger slots, means for effecting the placement of a filler strand upon the outer side of some stakes and the inner side of others, said means including packing fingers operating in said packing finger slots, means for holding the stakes in weaving relation to the fabric limiting means, and means for placing the filler strand under desired tension, whereby a tensioned fabric can be formed as a separate unit apart from the fabric limiting means. 80

3. An apparatus for weaving reed fabric and the like embodying therein fabric limiting means (against which the fabric is formed) formed with a plurality of spaced portions each having a relatively thin portion extending outwardly thereof, means for holding the stakes in weaving relation thereto, said spaced portions forming slots, and means for effecting the placement of a filler strand upon the outer side of some stakes and the inner side of others, said means including packing fingers operating in said packing finger slots, whereby a fabric can be formed as a separate unit apart from the fabric limiting means. 90

4. An apparatus for weaving reed fabric and the like embodying therein fabric limiting means, (against which the fabric is formed) formed with a plurality of spaced portions each having a relatively thin portion extending outwardly thereof, said spaced portions forming slots, means for effecting the placement of a filler strand upon the outer side of some stakes and upon the inner side of others, said means including packing fingers operating in said packing finger slots, and means for placing the filler strand under desired tension, whereby a tensioned fabric can be formed as a separate unit apart from the fabric limiting means. 100

5. An apparatus for weaving reed fabric and the like embodying therein fabric limiting means (against which the fabric is formed) formed with a plurality of spaced portions each having a relatively thin portion extending inwardly and a relatively thin portion extending outwardly thereof, means for holding the stakes in weaving relation thereto, said spaced portions forming slots, and means for effecting the placement of a filler strand upon the outer side of some stakes and the inner side of others, said means including packing fingers operating 110

in said packing finger slots, whereby a fabric can be formed as a separate unit apart from the fabric limiting means.

6. An apparatus for weaving reed fabric and the like embodying therein fabric limiting means, (against which the fabric is formed) formed with a plurality of spaced portions having rounded outer edges, means for holding the stakes in weaving relation thereto, said spaced portions forming slots, and means for effecting the placement of a filler strand upon the outer side of some stakes and the inner side of others, said means including packing fingers operating in said packing finger slots, whereby a fabric can be formed as a separate unit apart from the fabric limiting means.
7. An apparatus for weaving reed fabric and the like embodying therein fabric limiting means against which the fabric is formed, means for holding the stakes in weaving relation thereto, means having a plurality of grooves in alignment with the stake holding means for receiving the free ends of the stakes and normally retaining them, means for actuating the free ends of the desired stakes to project them from said grooves, means for holding the ejected stakes in ejected position for a period to permit placement of the filler strand, and means for inserting the filler strand, whereby a fabric can be formed as a separate unit apart from the fabric limiting means.
8. An apparatus for weaving reed fabric and the like embodying therein fabric limiting means against which the fabric is formed, means for holding the stakes in weaving relation thereto, means having a plurality of grooves in alignment with the stake holding means for receiving the free ends of the stakes and normally retaining them, means for actuating the free ends of the desired stakes to eject them from said grooves, means for holding the ejected stakes in ejected position for a period to permit placement of the filler strand, means for holding the ejected stakes in alignment with said grooves when in ejected position, and means for returning said ejected stakes to their proper grooves after the insertion of the filler strand, whereby a fabric can be formed as a separate unit apart from the fabric limiting means.

9. An apparatus for weaving reed fabric and the like embodying spaced plates, fabric limiting elements extending between said plates, means arranged adjacent one of said plates and formed to hold the stakes at one end and to position them in weaving relation to the fabric limiting elements, means formed in the other plate to receive the free ends of the stakes and to hold them in proper spaced relation, a helical spring surrounding said plate and positioned to permit placement of the free ends of the stakes

between oppositely disposed portions thereof, means for projecting desired stake ends into said spaces, and means for inserting the filler strand at the point where the stakes are projected.

10. An apparatus for weaving reed fabric and the like embodying spaced plates, fabric limiting elements extending between said plates, means arranged adjacent one of said plates and formed to hold the stakes at one end and to position them in weaving relation to the fabric limiting elements, means formed in the other plate to receive the free ends of the stakes and to hold them in proper spaced relation, a helical spring surrounding said plate and positioned to permit placement of the free ends of the stakes between oppositely disposed portions thereof, means for mounting the spring in proper relation to the plate and stakes, means for projecting desired stake ends into said spaces, and means for inserting the filler strand at the point where the stakes are projected.

11. An apparatus for weaving reed fabric and the like embodying therein spaced plates, fabric limiting elements extending between said plates, means arranged adjacent one of said plates and formed to hold the stakes at one end and to position them in weaving relation to the fabric limiting elements, means formed in the other plate to receive the free ends of the stakes and to hold them in proper spaced relation, a helical spring surrounding said plate and positioned to permit placement of the free ends of the stakes between oppositely disposed portions thereof, means for projecting desired stake ends into said spaces, and means for inserting the filler strand at the point where the stakes are projected, said means being interposed between the spring and the edge of said plate.

12. An apparatus for weaving reed fabric and the like embodying spaced plates, fabric limiting elements extending between said plates, means arranged adjacent one of said plates and formed to hold the stakes at one end and to position them in weaving relation to the fabric limiting elements, means formed in the other plate to receive the free ends of the stakes and to hold them in proper spaced relation, a helical spring surrounding said plate and positioned to permit placement of the free ends of the stakes between oppositely disposed portions thereof, means for projecting desired stake ends into said spaces and means for inserting the filler strand at the point where the stakes are projected, said means being interposed between the spring and the edge of the plates, means for spacing and holding the spring in proper relation to the plate and stake holding means, said spring holding means being formed to re-position

the spring when it returns to the plate after passing the filler strand inserting means in the event it becomes slightly displaced.

13. An apparatus for weaving reed fabric and the like embodying therein fabric limiting means, means for holding the stakes in weaving relation thereto, means for projecting the free ends of the desired stakes, means for holding the projecting stakes in projected position for the desired period, means for inserting the filler strand while the stakes are projected, and means tending to press the non-projected stakes away from the filler strand inserting means.

14. An apparatus for weaving reed fabric and the like embodying therein fabric limiting means, means for holding the stakes in weaving relation thereto, means for actuating the free ends of the stakes, timed means for projecting the free ends of the desired stakes, means for holding the projecting stakes in projected position for the desired period, means for inserting the filler strand while the stakes are projected, and means tending to press the non-projected stakes away from the filler strand inserting means.

15. An apparatus for weaving reed fabric and the like embodying therein fabric limiting means, means for holding the stakes in weaving relation thereto, means for projecting the free ends of the desired stakes, means for holding the projected stakes in projected position for the desired period, means for inserting the filler strand while the stakes are projected, means tending to press the non-projected stakes away from the filler strand inserting means, and means preventing undue movement of the non-projected stakes away from the filler strand inserting means.

16. An apparatus for weaving reed fabric and the like embodying therein fabric limiting means, means for holding the stakes in weaving relation thereto, positively actuated timed means for projecting the free ends of the desired stakes, means for holding the projected stakes in projected position for the desired period, means for inserting the filler strand while the stakes are projected, and means tending to press the non-projected stakes away from the filler strand inserting means.

17. An apparatus for weaving reed fabric and the like embodying therein fabric limiting means, means for positioning the stakes in weaving relation thereto, means for inserting the filler strand, means for placing the inserted filler strand into desired relation to the preformed fabric, and means acting to realign the stakes during the interval between the filler strand inserting periods, should the stakes become dis-aligned.

18. An apparatus for weaving reed fabric and the like embodying therein fabric limiting means, means for positioning the stakes in weaving relation thereto, means for in-

serting the filler strand, and means operating to align the stakes toward the weave point during the interval between the periods in which the filler strand is inserted should the filler strand become dis-aligned 70 in that direction.

19. An apparatus for weaving reed fabric and the like embodying therein fabric limiting means, means for positioning the stakes in weaving relation thereto, means for inserting the filler strand, and means operable to re-align the stakes in a direction away from the weave point prior to the approach of the stakes to the filler strand inserting point. 75

20. An apparatus for weaving reed fabric and the like embodying therein fabric limiting means, means for positioning the stakes in weaving relation thereto, means for inserting the filler strand, means operating to align the stakes toward the weave point during the interval between the periods at which the filler strand is inserted should the filler strand become dis-aligned in that direction and means operable to re-align the stakes in a direction away from the weave point prior to the approach of the stakes to the filler strand inserting point. 80

21. An apparatus for weaving reed fabric and the like embodying therein fabric limiting means, said means containing a plurality of slotted means for holding the stakes in weaving relation to the fabric limiting means and normally adjacent the outer portion of said slots, means for inserting the filler strand, means operating in said slots for placing the inserted filler strand into desired relation to the preformed fabric, and means carried by said filler strand placing means formed to project the stakes from said slots 90 should they become abnormally positioned therein. 95

22. An apparatus for weaving reed fabric and the like embodying therein fabric limiting means, said means containing a plurality of slotted means for holding the stakes in weaving relation to the fabric limiting means and normally adjacent the outer portion of said slots, means for inserting the filler strand, means operating in said slots 100 for placing the inserted filler strand into desired relation to the preformed fabric, and means for guiding the filler strand placing means in desired spaced relation to the walls of said slots. 110

23. An apparatus for weaving reed fabric and the like embodying therein a plurality of spaced fabric limiting elements, a filler strand packing arm arranged adjacent the space between contiguous fabric limiting elements, said arm carrying a finger normally projecting through said space and extending beyond the outer portion of the fabric limiting elements, and means for retracting the finger from the projected position to permit 115 125 130

same to pass under the filler strand at the feed point.

24. An apparatus for weaving reed fabric and the like embodying therein a plurality 5 of spaced fabric limiting elements, a plurality of filler strand packing mechanisms positioned for operation in the spaces between said fabric limiting elements, said filler strand packing mechanisms each comprising an arm carrying a finger and means normally causing the finger to project through said spaces and beyond the outer surface of the fabric limiting means, means for causing to and fro movement of each 10 packing arm and means for retracting the packing finger and for holding in retracted position during a period before and after the insertion of the filler strand.

25. An apparatus for weaving reed fabric 20 and the like embodying therein a plurality of spaced fabric limiting elements, a plurality of filler strand packing arms arranged adjacent the spaces between contiguous fabric limiting elements, each said packing arm 25 having a packing finger at its upper end and a weight at its lower end, means for causing the projection of said finger through the space between the fabric limiting elements and beyond the outer surface thereof, 30 a cam upon which said weights ride, said cam being formed and positioned to cause elevation of the weight and packing arm as they approach the filler strand inserting point, to hold the weights and packer arms 35 in elevated position for a period before and after the filler strand inserting period, and to permit the gradual descent of the weights until the packing fingers carry the inserted 40 filler strand into desired relation to the pre-formed fabric.

26. An apparatus for weaving reed fabric and the like embodying therein a plurality 45 of spaced fabric limiting elements, a plurality of filler strand packing arms arranged adjacent the spaces between contiguous fabric limiting elements, each said packing arms having a packing finger at its upper end and a weight at the lower end, means for causing the projection of said finger through 50 the space between the fabric limiting elements and beyond the outer surface thereof, a cam upon which said weights ride, said cam being formed and positioned to cause the elevation of the weight and packing arms 55 as they approach the filler strand inserting point and to hold the weights and packer arms in elevated position for a period before and after the filler strand inserting period and to permit the gradual descent of the weights until 60 the packing fingers carry the inserted filler strand into desired relation to the preformed fabric, means automatically causing the retraction of the filler strand packing fingers as the packing arm reaches its uppermost position, and means limiting the inward movement of the filler strand packing finger to prevent entire removal from the space between the contiguous fabric limiting elements.

29. A filler strand packing element comprising a weight, an arm mounted therein for swinging movement, and a spring extending between the weight and the arm and constantly tending to move the arm in a given direction.

30. A filler strand packing element comprising a weight, an arm mounted therein 130

27. An apparatus for weaving reed fabric and the like embodying therein a plurality of spaced fabric limiting elements, a plurality of filler strand packing arms arranged adjacent the spaces between contiguous fabric limiting elements, each said packing arm having a packing finger at its upper end and a weight at the lower end, means for causing the projection of said finger through the space between the fabric limiting elements 75 and beyond the outer surface thereof, a cam upon which said weights ride, said cam being formed and positioned to cause the elevation of the weight and packing arms as they approach the filler strand inserting 80 point and to hold the weights and packer arms in elevated position for a period before and after the filler strand inserting period and to permit the gradual descent of the weights until the packing fingers carry 85 the inserted filler strand into desired relation to the preformed fabric, and means automatically causing the retraction of the filler strand packing fingers as the packing arm approaches its uppermost position, and means for re-projecting the filler strand 90 packing finger at the desired time after the finger has passed the feed point.

28. An apparatus for weaving reed fabric and the like embodying therein a plurality 95 of spaced fabric limiting elements, a plurality of filler strand packing arms arranged adjacent the spaces between contiguous fabric limiting elements, each said packing arm having a packing finger at its upper end and a weight at the lower end, means for causing the projection of said finger through the space between the fabric limiting elements and beyond the outer surface thereof, a cam upon which said weights ride, said cam being 100 formed and positioned to cause the elevation of the weight and packing arms as they approach the filler strand inserting point and to hold the weights and packer arms in elevated position for a period before and after the filler strand inserting period and to permit the gradual descent of the weights until the packing fingers carry the inserted filler 105 strand into desired relation to the preformed fabric, means automatically causing the retraction of the filler strand packing fingers as the packing arm reaches its uppermost position, and means limiting the inward movement of the filler strand packing finger to prevent entire removal from the space between the contiguous fabric limiting elements.

31. A filler strand packing element comprising a weight, an arm mounted therein for swinging movement, and a spring extending between the weight and the arm and constantly tending to move the arm in a given direction.

32. A filler strand packing element comprising a weight, an arm mounted therein 130

for swinging movement, and a spring extending between the weight and the arm and acting to pull the arm toward the weight.

31. A filler strand packing element comprising a weight, an arm mounted therein for swinging movement, and a spring extending between the weight and the arm and constantly tending to move the arm in a given direction, said arm being slotted and a pivot pin passing through the slot and spring means normally causing the pivot pin to rest in the slot adjacent one end thereof and permitting sliding movement of the arm as and for the purpose specified.

32. Apparatus for weaving reed fabric and the like embodying therein means for holding a plurality of stakes in desired spaced relation, means for inserting a filler strand, and means for putting the filler strand under desired tension, said means comprising a frictionally retarded wheel having a conical face around which the filler strand passes.

33. Apparatus for weaving reed fabric and the like embodying therein means for holding a plurality of stakes in desired spaced relation, means for inserting a filler strand, and means for putting the filler strand under desired tension, said means comprising a wheel having a conical face around which the filler strand passes, mounted for rotation on a shaft, a friction disc engaging the wheel, and adjustable spring means for pressing the friction disc against the wheel.

34. Apparatus for weaving reed fabric and the like embodying therein means for holding a plurality of stakes in desired spaced relation, means for simultaneously inserting a plurality of filler strands, and means for putting said filler strands under desired tension, said means comprising a plurality of conical faces equal in number to the filler strand simultaneously inserted, means separating the conical faces and means frictionally retarding rotation thereof.

35. Apparatus for weaving reed fabric and the like embodying therein means for holding a plurality of stakes in desired spaced relation, means for inserting a filler strand, and means for putting the filler strand under desired tension, said means comprising a frictionally retarded wheel having a conical face around which the filler strand passes, and a crimped top adjacent

the conical face through which the filler strand passes.

36. Apparatus for weaving reed fabric and the like embodying therein fabric limiting means against which the fabric is formed, means for holding the stakes in weaving relation thereto, and a head plate removably mounted over the fabric limiting means and carrying devices formed to project desired stakes and to insert the filler strand.

37. Apparatus for weaving reed fabric and the like embodying therein a filler strand packing mechanism guide portion, a fabric limiting portion superposed thereon against which the fabric is formed, a head portion superposed upon the fabric limiting portion, and filler strand packing mechanism having a portion slidingly co-acting with the filler strand packing mechanism guide portion and the fabric limiting means.

38. Apparatus for weaving reed fabric and the like embodying therein a vertical stationary shaft, a filler strand packing mechanism guide portion mounted for concentric rotation around the shaft, a fabric limiting portion mounted for concentric rotation around said shaft, a head plate and associated stake control means mounted on the fabric limiting portion for rotation therewith, stake projecting mechanism non-rotatably arranged adjacent said head plate, and means for imparting rotation to said rotatable portions.

39. Apparatus for weaving reed fabric and the like embodying therein a vertical stationary shaft, a filler strand packing mechanism guide portion mounted for concentric rotation around the shaft, a fabric limiting portion mounted for concentric rotation around said shaft, a head plate and associated stake control means mounted on the fabric limiting portion for rotation therewith, stake projecting mechanism non-rotatably arranged adjacent said head plate and filler strand inserting means adjacent the edge of said head plate including means holding same against rotation.

In testimony thereof, I hereunto set my hand, this 9th day of May, 1917, in the presence of two subscribing witnesses.

M. B. LLOYD.
